DESIGN FOR A BEVERAGE GLASS OR SIMILAR ARTICLE

William H. Hommel, Sandusky, Ohio

Application April 11, 1934, Serial No. 51,373

Term of patent 14 years

To all whom it may concern:

Be it known that I, WILLIAM H. HOMMEL, a citizen of the United States of America, residing at Sandusky, in the county of Erie, and State of Ohio, have invented a certain new, original, and ornamental Design for a Beverage Glass or Similar Article, of which the following is a specification, reference being had therein to the accompanying drawing, forming a part thereof, in which the figure is a perspective view of a beverage glass showing my new design.

I claim:

The ornamental design for a beverage glass or similar article substantially as shown.

WILLIAM H. HOMMEL.
